UNITED STATES PATENT OFFICE.

ADOLPHUS H. FORSTNER, OF NEWPORT, KENTUCKY.

DESIGN FOR A COMB AND BRUSH POCKET.

Specification forming part of Design No. **6,195**, dated October 8, 1872.

To all whom it may concern:

Be it known that I, ADOLPHUS H. FORSTNER, of Newport, in the county of Campbell and State of Kentucky, have invented a new and original Design for a Comb and Brush Pocket, of which the following is a specification:

The accompanying photograph fully illustrates my invention.

This invention relates to a new comb and brush pocket which can be suspended from a wall or other support, and which in appearance is ornamental and convenient for use.

The back of the pocket is upright and contains three rosettes, of which the uppermost

one has a central aperture to admit the fastening nail or pin. From the upper rosette is suspended an acorn, as shown. Vase-like ornaments are applied to the ends of the upright back, where the semi-cylindrical pocket joins it, as shown. Moldings decorate the rim of the pocket at the top and bottom.

I claim as my invention—

The design for a comb and brush pocket, as shown.

ADOLPHUS H. FORSTNER.
